LIVESTOCK EAR TAG CLAMP HOLDING AND CLOSING PLIERS

Herman J. McMurray, Seal Beach, Calif.
(P.O. Box 18948, Los Angeles, Calif. 90018)

Filed Aug. 6, 1968, Ser. No. 13,042

Term of patent 14 years

Int. Cl. D8—01

U.S. Cl. D54—13

FIG. 1 is a three-dimensional pictorial view of livestock ear tag clamp holding and closing pliers, showing my new design;

FIG. 2 is a near side elevational view thereof drawn to a somewhat larger scale, it being understood that the opposite side thereof is identical in appearance although positionally and directionally reversed from the showing of FIG. 2;

FIG. 3 is a top plan view thereof, it being understood that a bottom plan view thereof would be identical in appearance to that shown in FIG. 3;

FIG. 4 is a front elevational view thereof; and

FIG. 5 is a rear elevational view thereof.

I claim:

The ornamental design for livestock ear tag clamp holding and closing pliers, substantially as shown and described.
